INVENTOR

John A. MCKAY,
BY
Premack Kay
ATTORNEY

UNITED STATES PATENT OFFICE.

JOHN A. MCKAY, OF PORTLAND, MAINE.

DAM, DIKE, AND THE LIKE.

Application filed October 23, 1918. Serial No. 259,330.

To all whom it may concern:

Be it known that I, JOHN A. MCKAY, a citizen of the United States, residing at Portland, in the county of Cumberland, 5 State of Maine, have invented certain new and useful Improvements in Dams, Dikes, and the like; and I do hereby declare the following to be a full, clear, and exact description of the invention, such as will enable 10 others skilled in the art to which it appertains to make and use the same.

My present invention has relation to an improved form of water confining structure, applicable to the construction of dams, 15 levees, seawalls and the like, and more particularly to be used in relatively shallow water, where large areas are to be confined for the purpose of reclamation.

My invention has the advantage of being 20 capable of construction by a relatively inexpensive and rapid method of operation, which is hereinafter described.

I have shown a certain preferred embodiment of my invention for purposes of description in the accompanying drawings, 25 wherein Figure 1 is a plan, with the middle portion removed, showing the two ends of the core of a long dike or dam; Figure 2 is a side elevation of the same; Figure 3 is a dia- 30 grammatic cross-section of the dike; Figure 4 is a cross-section of another style of dike; Figure 5 is a plan view illustrating one method of making the connection of the adjacent ends of two sections of the core; Figure 35 6 is a perspective view of one of the ends of the sections shown in Figure 5; and Figure 7 is a longitudinal vertical section illustrating another method of making the connection.

Referring to the particular embodiment illustrated, a suitable even bearing or bed is first prepared along the line of the intended structure as by dredging, blasting or otherwise excavating the bottom or by building or 45 laying earth, broken stone, concrete mats or other suitable material on the bottom or erecting a support or cradle to form a bed above the bottom. In some instances the natural bed or bottom may be utilized.

A hollow core with closed ends or with 50 bulkheads set in from the ends a suitable distance to permit the forming of joints as hereinafter described, is floated above the bed and filled with earth, sand, liquid cement, concrete or other heavy material and

sunk to a bearing on the bed. The core is sunk in successive sections connected at their ends so as to form a continuous structure, after which a covering of rock, earth, concrete or any combination of suitable materials may be built around the core to complete the structure which is desired. The core is preferably of such a height that, when sunk in position, it extends above the water level so as to permit access to the openings on its upper side; and is preferably of varying diameters to correspond with the depths of water at different points. In Figure 1 a core A of gradually increasing diameter toward the center is shown anchored at 60 its ends between piers B near the shore line C. The upper edge of the core is substantially horizontal and the lower edge is roughly parallel with the bottom of the waterway; being located slightly below the bottom and 70 lying in a previously excavated trench D, Figure 3. When the core A has been sunk in place the structure is completed by placing around it a body E of stones or other suitable material, finishing it off to the desired shape and usually terminating at the top in a flat roadway. The material E may for example, be rocks dumped on either side of the core and sand pumped from the bottom may be used to fill the interstices between the rocks. 85

Figures 5 and 6 illustrate one particular shape and style of joint. The tubes A are built up of riveted steel plates in the usual way having bulkheads F near their ends and having at one end tongues G at the top and bottom. The adjoining section has at its adjacent end grooves H adapted to fit loosely upon the tongues G. The tongues G and grooves H are made with their edge faces 95 vertical so that, one section being in place the next can be lowered upon it with the grooves engaging the tongue. The tongues and grooves are preferably of the dove-tailed style shown and provide an interlocking connection. Preferably also the end of the sunken section is provided with a flange or saddle J extending around approximately the lower half of the section and extending beyond the end so that the next section may 100 be dropped into such saddle; and the end of the next section which is being lowered is provided with a similar flange K fastened to and projecting beyond its ends and extending around substantially its upper half so as to 105 110

lap over the end of the previously sunk section. Or the construction may be simplified as in Figure 7 by using only the flanges J and K without the tongues and grooves of Figures 5 and 6. Beyond the bulkheads of each of the sections, openings L are provided in the top of the tube, and after the sections are interlocked in the manner indicated, concrete is poured in through the openings L to fill the two ends and fasten them rigidly and permanently together. The concrete may be reinforced by rods, wires or other metal shapes embedded therein. The sections as they are sunk are weighted through openings M provided at intervals in the top of the sections.

Each of the sections A may be built on shore or on lighters in protected places and they may be of a length which will vary in accordance with conditions. For example, they may be from one hundred to one thousand feet long and may vary in diameter from ten feet or less to forty feet or more. Each section can be extended out upon the water in a quiet place as it is being constructed. After it is completed and bulkheads provided at its ends it can be towed to the site of the work and located with the aid of anchors or other suitable means over the line of the trench or bearing provided for it. It can then be weighted and lowered gradually and with very accurate control to its bearing.

The invention permits of choosing the time for sinking the core sections, so that this can be done during quiet periods when weather, wind, depth of water and other conditions are most favorable, and during periods of slack water where there are tides. The operation of sinking the core can be so quickly performed that the invention permits of the builder's availing himself of comparatively brief periods of time when the natural conditions are most favorable. After the sinking of one section of the core the next section is floated to place and sunk carefully so that its end will register with the free end of the next previous section. A solid continuous joint is then made as above described. The sinking of the different sections of the core may be accomplished simultaneously at a number of points in the length of the proposed dike or progressively from one end to the other. The application of the material surrounding the core may take place progressively as the core sections are sunk, or if preferred the entire core may be sunk before the body of the dike is built up around it.

Where the depth of water makes it desirable the core may be lowered in a plurality of tiers sunk one upon another successively to bring the core to the desired height. Figure 4 illustrates such a construction. Instead of a single core A, as in Figure 3, three

such cores are used, two on the bottom and the third resting on the lower two. This figure shows a feature which may also be applied with various styles of core, namely, a facing N of granite blocks on the faces of the dike, the loose rock, sand cement or other filling material being protected by the facing. Such a facing may be applied on both sides of the dike or on one side only and it may be made of granite blocks, or of concrete blocks, poured cement or concrete or other suitable material.

The construction shown may be widely varied in the design of the parts and in the material of which they are made without departing from the invention as defined in the claims hereinafter, and various additional features known to skilled engineers may be provided, such for example, as anchoring means for holding the core in position on its bed, a screen of piling or other material to prevent the water from scouring out the earth from under the bottom of the core and braces such as piers or piles at intervals in the length of the structure.

It is not necessary in all cases to apply a body of material around the core. The latter itself may constitute the dike or other structure contemplated. For example, in the case of a breakwater the tubular sections may be made to rest at intervals on piers, the continuous structure being located at such a height as to extend partly above the surface to break the force of the waves and leaving a clear space below through which the water may pass or circulate.

An important advantage of the construction, besides the facility of erection and other advantages referred to in detail above is its continuity and the strength of the connections between the successive parts so that the structure or the core which forms the principal part thereof is practically a unit from end to end and the ends of which are securely anchored to the shores. The core is strengthened by the material introduced into the core and constituting a permanent part of the dike, this material being exposed through the open top of the core so that it may always retain a certain amount of water which will prevent it from shrinking.

What I claim is:

1. In a water confining structure of the character described, a continuous core composed of a series of substantially horizontal pipe sections having abutting ends rigidly joined, a closed bulkhead at the end of each section, interlocking hollow joints rigidly joining the sections outside of the bulk heads thereof and a filling of mineral material within said joints.

2. The structure set forth in claim 1 hereof, wherein a plurality of superposed series of pipes is employed.

3. The structure set forth in claim 1 here-

of, wherein the top of the series of pipes has openings at intervals adapted to permit filling of said pipes from above.

4. The structure set forth in claim 1 hereof, wherein certain sections of pipe are made tapering to accommodate the structure to differences in depth of the water where the structure is set up.

5. The structure set forth in claim 1 hereof wherein the core is round in cross section to facilitate settling in its bed under the action of waves and currents. 10

In testimony whereof, I affix my signature.

JOHN A. MCKAY.
